United States Patent Office

Des. 218,774
Patented Sept. 22, 1970

218,774

KNITTED TEXTILE FABRIC, OR SIMILAR ARTICLE

Robert Hammer, Merrick, N.Y. (% Sweater-Bee by Banff, Ltd., 1410 Broadway, New York, N.Y. 10018)

Filed Dec. 16, 1968, Ser. No. 14,969

Term of patent 3½ years

Int. Cl. D5—02

U.S. Cl. D47—2

FIG. 1

FIG. 2

FIG. 1 is a plan view of a knitted textile fabric, or similar article, showing my new design; and

FIG. 2 is a plan view of the reverse face thereof.

I claim:

The ornamental design for a knitted textile fabric or similar article, as shown.
